SELECTIVELY POSITIONED BRUSH NOZZLE

Oliver L. Allen, Riverside, Conn., assignor to Electrolux Corporation, Old Greenwich, Conn., a corporation of Delaware

Filed Oct. 26, 1954, Ser. No. 464,803

6 Claims. (Cl. 15—371)

This invention relates to the art of vacuum or suction cleaner operation and more particularly to a multi-purpose nozzle or cleaning tool which may be selectively adapted for use on rugs having various depths of pile, or on fabric or similar floor coverings or alternatively on linoleum or even on plain hard surfaces such as wood.

Heretofore, wand manipulated nozzles for air suction cleaners have necessitated at least two totally different replaceable nozzles for use on such distinctively different surfaces as pile rugs and hard wood or similar plain surfaces.

It is an object of this invention to provide a simple cleaning tool for a vacuum cleaner which tool may be selectively used as a rug cleaning nozzle, a combined rug cleaning and rug brushing nozzle or as a brush nozzle specifically designed for cleaning a plain, hard surface such as linoleum or a wooden floor.

It is a further object of this invention to provide a new and improved surface cleaning tool.

Another object is to provide a cleaning tool having a brush which is selectively operable to various positions with respect to the surface being cleaned.

Further objects and still other advantages of this invention will become apparent upon considering the following description and accompanying drawings wherein:

Figure 1 is a top plan view of a nozzle embodying this invention;

Figure 2 is a bottom plan view with the nozzle bottom cover and brush partly broken away to show the interrelation of the various nozzle parts;

Figure 3 is a section taken on the line 3—3 of Figs. 1 and 2, showing the rear brush cams with their three brush positions;

Figure 4 is a section taken on the line 4—4 of Figs. 1 and 2, showing the front brush cams with their two brush positions;

Figure 5 is a side plan view of the nozzle with the floor brush in operating position;

Figure 6 is a vertical sectional view of the nozzle taken on the line 6—6 of Fig. 1;

Figure 7 is a partial sectional view taken on the line 7—7, Fig. 4, and showing more complete structural details of the brush actuating mechanism;

Figure 8 is a bottom plan view of a modification with portions of the brush and casing partly broken away to show the interrelation of the various parts of this particular embodiment;

Figure 9 is a section taken on the line 9—9, Fig. 8, showing the floor brush in extended position ready for use;

Figure 10 is a section taken on the line 10—10, Fig. 8, showing the floor brush in lifted position and the nozzle ready for use solely as a rug nozzle;

Figure 11 is a partial section of the nozzle taken on the line 11—11, Fig. 10, showing the brush locked up against an upper stop;

2

Figure 12 is a vertical section of the nozzle taken on the line 12—12, Fig. 10;

Figure 13 is a cross section taken along the line 13—13, Fig. 10, showing the brush locked up in retracted position (see cam arrangement Fig. 16);

Figure 14 is a similar cross sectional view to that shown in Fig. 13 with the control knob turned counterclockwise through a 90° arc, showing the left half of the brush (front side) locked up in retracted position while the right half of the brush (rear side) is floating against a downward spring bias (see cam arrangement Fig. 17);

Figure 15 is a similar cross section to that shown in Fig. 13 with the control knob turned through a 180° arc, showing the entire brush surface locked down into floor cleaning position (see cam arrangement Fig. 18); and

Figures 16, 17 and 18 show the orientation of the front and back cam members in the positions shown in Figs. 13, 14 and 15, respectively, when looked at from the control knob end of the nozzle.

The cleaner nozzle forming the subject matter thereof comprises a single nozzle opening having associated therewith a brush which is selectively movable to operative and inoperative positions and in one modification is selectively movable so that only one portion of the brush element is in operative position. A slideable or rotatable cam device is used to retract or extend the spring biased brush into or out of its seat so as to make the nozzle adaptable for various surface cleaning operations.

Referring now more broadly to the drawings wherein the subject matter of this invention is shown in two embodiments, the conventional wand and flexible suction hose not being shown, Figs. 1 through 7 illustrate one embodiment. Cleaning tool 10 comprises a body portion

12 having a central tubular portion 14, to the rear of which is mounted a swivelled elbow 16 (more clearly shown in cross section in Fig. 6). Elbow 16 is adapted to receive a wand or vacuum cleaner suction hose for connection to the conventional source of suction. The single nozzle opening serves both as a pile rug and a bare surface cleaning unit. This is effected by arranging a retractable peripheral brush element around the nozzle opening in such a manner that it can be retracted within a brush channel or brush recess or alternatively exposed and urged outwardly into engagement with a surface to be cleaned, namely a linoleum or similar hard surface.

Referring now in more detail to the drawings, wherein a number of nozzles are shown, a single suction passage-way 18, Fig. 2, leads from the nozzle opening to the suction conduit or connector elbow 16 which in turn is mounted on a wand or suction hose.

The brush structure 20, Fig. 4, is mounted within a peripheral chamber 24 for slideable movement and extends all around the periphery of the nozzle opening 18. Brush structure 20 slidably engages the lateral edges of slot or chamber 24 and thus is kept in lateral position without forward or backward displacement or sidewise displacement. Four sockets 26, Figs. 2 and 3, are formed in the body portion 12 to receive springs 28, Fig. 6, which press the brush structure 20 downward and outward from the chamber 24. The extent of the downward movement of brush 20 is limited by pins 30 secured to the brush structure, Fig. 3 which ride on cam surfaces 31a and 32a of rear brush cam 31 and cam surfaces 41a and 42a, Figs. 4 and 7, of front brush cam 41.

Both cams 31 and 41 are operatively connected to manipulating handle 50, Figs. 1, 3 and 4, which is adapted for sliding motion as indicated by the arrow, Fig. 1. An intermediate position of handle 50 locks the front half 70 of the brush structure 20 in retracted position 41b, 42b, Fig. 4, while the rear half of brush structure 20 is left in a floating position 31b, 32b, Fig. 3, spring biased.

against the rug or other surface being cleaned (see Fig. 14 for this corresponding position of the brush structure 120 as shown transversely in another embodiment). With handle 50 moved all the way to the left, Fig. 1, both the front and rear portions of the brush structure 20 are locked in completely retracted positions within chamber 24 by cam surfaces 41c, 42c, Fig. 4 and 31c, 32c, Fig. 3, respectively (see Fig. 13 for this corresponding position of the brush structure 120 as shown transversely in another embodiment).

A bumper or guard strip 60, Figs. 2, 3, 4 of rubber or similar material is securely anchored in a groove in the outer edge of the body 12 of the nozzle. End glider plates 62, 64 serve to hold guard strip 60 in place. A flexible cover, designated by 66 at the rear and 68 at the front, Fig. 6, serves as a sealing member to keep dust, lint, etc., out of the cam mechanism. The outer edge of members 66 and 68 is imbedded in guard strip 60 while the inner edge of each serves as a guide to the outer side of brush structure 20. The bristles 21 of brush structure 20 are shown in outward or floor cleaning position in Figs. 1 through 7. Figs. 10 through 13 show the bristles 21 of brush structure 120 in retracted position.

The modification shown in Figs. 8 through 18 inclusive is a somewhat similar embodiment to that described above. Swivel elbow 116, Figs. 8 and 12, is mounted on nozzle body portion 112 in the usual fashion. A wand (not shown) conducts suction through elbow 116 to nozzle passageway 118 and the opening of the nozzle to clean a pile carpet or when the brush structure 120, Figs. 9 and 10 is lowered, to clean a hard surface such as linoleum or a bare floor.

The brush structure 120 comprises a front framework 100, Figs. 10 and 12 having upper and lower cam actuated surfaces 100a and 100b, respectively, and a rear framework 101, Figs. 9, 12, and 13, likewise having upper and lower cam actuated surfaces 101a and 101b, respectively.

In this embodiment, the rear portion, only, of the brush structure 120 is spring biased to downward position by springs 128 held in sockets 126, Fig. 12. Cam 100c, Figs. 12 through 18, affixed to shaft 110a when turned by thumbscrew or knurled knob 110 so as to be in positions shown in Figs. 16 and 17 locks the front portion of brush structure 120 up in its positions shown in Figs. 13 and 14, respectively. This is effected by cam surface 100c pressing upwards against upper actuated surface 100a. In the rear part of the brush structure 120, next to knurled knob 110, cam 101c as shown in Figs. 13 and 16 at first locks the back portion of brush structure 120 up in its retracted position; a quarter turn of knob 110 counterclockwise causes cam 101c to assume the position shown in Fig. 17 and spring 128 forces cam actuated surface 101a down on the lower midway dwell of cam 101c as shown in Fig. 14. This causes the rear half of brush structure 120 to serve as a free floating, downwardly spring biased element which readily removes thread, lint, etc., which is difficult to remove with an unaided air stream. Thus ordinary air cleaning is supplemented by the cleaning action of bristles 21 which are pressed against the surface being cleaned by the free floating action of springs 128.

An additional 90° counterclockwise turning of knob 110 to the position shown in Fig. 18, causes both cams 100c and 101c to lock the entire brush structure 120 into its outwardly extending position shown in Fig. 15 by the action of cams 100c and 101c pressing cam actuated surfaces 100b and 101b downwardly. This position, suitable for cleaning hard surfaces with the brush elements 21 extended is also shown in Fig. 9.

The front and rear framework 100 and 101, respectively, are held together by a top plate 105 suitably welded or otherwise fastened thereto and the whole unit

is covered by a rubber sheet 106 suitably moulded thereover and over the upper portion of nozzle body 112 as shown in Fig. 12 to completely enclose all the moving parts. A pair of slots 109, 111 Fig. 9, through which pass guide pin 109a and shaft 110a, respectively (affixed in the nozzle body 112), serve to maintain alignment of the upwardly and downwardly moving elements 100 and 101 of brush structure 120. A stop 150, Fig. 11, affixed by a screw to the interior of nozzle body 112 arrests the upward travel of brush structure 120. Various flexible sealing covers such as 130, Fig. 12, complete the detail of the complete nozzle assembly.

It is to be understood that the examples given are merely illustrative and not limitative embodiments of this invention which is to be determined solely by the scope of the appended claims.

What I claim is:

1. In a vacuum cleaner tool, a member having a suction passage therethrough terminating in a nozzle inlet disposed in a normally horizontal plane, means defining a chamber entirely surrounding said nozzle inlet and having an opening adjacent to said plane, a peripheral brush in said chamber having front and rear portions each reciprocably mounted and movable upwardly and downwardly independently with respect to said plane, resilient means urging said brush downwardly with respect to said plane, a first cam cooperating with said front portion, a second cam cooperating with said rear portion, and an operating member for moving said cams in unison, said cams being so shaped that in one position of said operating member said cams retain the respective brush portions in retracted position above said plane, in a second position said first cam retains said front portion in retracted position while said second cam releases said rear portion for projection downwardly below said plane by said resilient means so as to yieldably engage a surface being cleaned, and in a third position said cams retain the respective portions in lowered position below said plane.

2. In a vacuum cleaner tool, a member having a suction passage therethrough terminating in a nozzle inlet disposed in a normally horizontal plane, means defining a chamber entirely surrounding said nozzle inlet and having an opening adjacent to said plane, a brush in said chamber having front and rear portions each reciprocably mounted and independently movable upwardly and downwardly with respect to said plane, resilient means urging said brush downwardly with respect to said plane, a first cam plate slidably mounted in said member and cooperating with said front portion, a second cam plate slidably mounted in said member and cooperating with said rear portion, and an operating member for moving said cam plates in unison, said cam plates being formed with cam surfaces so shaped that in one position of said operating member said cam plates retain the respective portions in inoperative position above said plane, in a second position said first cam plate retains said front portion in said inoperative position while said second cam plate releases said rear portion for projection downwardly below said plane by said resilient means so as to yieldably engage a surface being cleaned, and in a third position said cam plates retain the respective portions in lowered position below said plane.

3. In a vacuum cleaner tool, a member having a suction passage therethrough terminating in a nozzle inlet disposed in a normally horizontal plane, means defining a chamber entirely surrounding said nozzle inlet and having an opening adjacent to said plane, a brush in said chamber having front and rear portions each reciprocably mounted and independently movable upwardly and downwardly with respect to said plane, resilient means urging said brush downwardly with respect to said plane, an operating shaft rotatably mounted in said member, a first rotary cam secured to said shaft and cooperating with

said front portion, and a second rotary cam secured to said shaft and cooperating with said rear portion, the profiles of said cams being such that in one position of said shaft said cams position the respective portions in inoperative position above said plane, in a second position said first cam positions said front portion in said inoperative position while said second cam releases said rear portion for projection downwardly below said plane by said resilient means so as to yieldably engage a surface being cleaned, and in a third position said cams position the respective portions in lowered position below said plane.

4. In a vacuum cleaner tool, a member having a suction passage therethrough terminating in a downwardly opening nozzle disposed in a normally horizontal plane, means defining a chamber entirely surrounding said nozzle and open at the lower edge thereof, a peripheral brush including front and rear portions mounted in said chamber and movable upwardly and downwardly with respect to said plane, resilient means urging said brush downwardly, and a single member operative from the exterior of said chamber and including a portion adjustable to a first setting for positioning the front brush portion in a retracted position above said plane, and releasing the rear portion thereof for projection downwardly below said plane subject to the pressure of said resilient means to yieldingly engage a surface being cleaned, a second portion adjustable to a second setting for positioning both portions of said brush in retracted position above said plane, and a third portion adjustable to a third setting for positioning both of said brush portions in a projected position below said plane.

5. In a vacuum cleaner tool, a member having a suction passageway therethrough terminating in a downwardly opening cleaning nozzle disposed in a normally horizontal plane, a brush structure reciprocably mounted on said member in circumscribed relation to said nozzle for movement downwardly and upwardly with respect to said plane, said brush including front and rear portions, cam means on said member including portions sequentially engageable with said front and rear brush portions for reciprocating said brush portions upwardly and downwardly with respect to said plane to extend and retract a lower effective end of each brush portion to below and above said plane independently and in combination, a single manually operable member for actuating

said cam means, and resilient means engaging said brush structure and biasing at least a portion thereof into operative free floating position in the absence of pressure applied by said cam means.

- 5 6. In a vacuum cleaner tool, a nozzle member having a suction passage therethrough terminating in a nozzle inlet disposed in a normally horizontal plane, a brush having front and rear portions each reciprocably mounted with respect to said nozzle member and independently movable upwardly and downwardly relative to said plane, resilient means urging said brush downwardly relative to said plane, first cam means cooperating with said front portion, second cam means cooperating with said rear portion, and operating means for moving said cam means in unison, said cam means being so shaped that in one position of said operating means said cam means retain the respective brush portions in raised position above said plane, in a second position said first cam means retains said front portion in raised position while said second cam releases said rear portion for downward movement by said resilient means to below said plane so as to yieldably engage a surface being cleaned, and in a third position said cam means retains both portions in lowered position below said plane.
